FRICITION DEVICE FOR FILLING CARRIERS

Sherwood O. Dodge, Medford, Mass., assignor to
Guaranteed Parts, Inc., Allston, Mass., a cor-
poration of Massachusetts

Application July 31, 1934, Serial No. 737,754

6 Claims. (Cl. 139—251)

This invention relates broadly to a friction device for the filling carriers of a filling replenishing loom and particularly to a holder by means of which a friction device may be effectively held in a position to yieldingly engage that filling carrier located in a rotary hopper for carriers which is located in transferring position and is next to be transferred to the shuttle.

The principal object of the invention is to provide a simple effective device for engaging the filling carrier which is located in transferring position and creating sufficient pressure thereon to prevent said carrier from rotating in the hopper as a consequence of a vibration of the latter, to the end that the filling will not unwind from the carrier and be subjected to the danger of breaking during the subsequent operation of the shuttle after the carrier has been transferred thereto.

Another object of the invention is to provide a holder of novel construction for a flexible filling engaging or friction member, said holder being adjustably mounted upon a suitable support and having a resilient arm embodied therein upon which the friction member is also adjustably mounted, all to the end that the proper tension may be placed upon the filling carrier for the purposes mentioned.

The invention consists in a friction device for filling carriers as set forth in the following specification and particularly as pointed out in the claims thereof.

Referring to the drawing:—

Fig. 1 represents a vertical sectional elevation of a portion of a filling replenishing loom, including a lay having a shuttle mounted thereon, a hopper for filling carriers, and a transfer mechanism for said carrier, a friction device for filling carriers embodying my invention being illustrated associated therewith.

Fig. 2 is a plan view partly broken away and illustrated in section of a portion of the mechanism illustrated in Fig. 1 and including the friction device of this invention.

Fig. 3 is a side elevation of the friction device.

Fig. 4 is a detail transverse section taken on the line 4—4 of Fig. 3.

Fig. 5 is a detail plan view of the flexible friction member.

Fig. 6 is a side elevation of a modified embodiment of the device.

Like numerals refer to like parts throughout the several views of the drawing.

In the drawing, referring to Figs. 1 to 5 inclusive, 5 represents a portion of the frame of a fill-

ing replenishing loom, 6 a lay, 7 a shuttle box and 8 a shuttle positioned in said box. Mounted upon the frame 5 is a stand 9 for a rotary bobbin disc 10 constituting a portion of a hopper 11 in which a plurality of bobbins 12 constituting filling carriers are mounted in a well-known manner. Mounted on the stand 9 is a fixed transfer stud 13 upon which is pivotally mounted a transfer 14 provided with a downwardly projecting arm 15 to which a transfer dog 16 is pivotally attached at 17. The dog 16 is adapted to be engaged by a bunter 18 mounted on the lay 6 to effect the operation of the transfer 14 in a well-known manner and cause a bobbin 12 which is located in transferring position in the hopper 11 to be forced downwardly from said hopper into the shuttle 8.

All of the parts hereinbefore mentioned are old and their operation is well known in the art. It is also well known that portions of this mechanism, particularly the hopper 11, are caused to vibrate excessively with the result that there is a tendency for the filling carriers 12 to rotate upon the portions of the hopper upon which they are mounted, thereby causing the filling to unwind. When this happens it is a common occurrence after the filling carrier has been transferred to the shuttle for the filling thread to break when the shuttle is driven across the lay with the result that the loom is caused to stop and production therefore is stopped until the loom is again started.

The friction device of this invention is mounted upon an arm 19 which is rigidly fastened to the transfer stud 13 by a set screw 20. A finger 22 constituting a top holder is rigidly secured in any suitable manner to a pivot member 21 which is mounted to rotate in a bearing provided at the outer extremity of the arm 19. Mounted upon the opposite end portion of the pivot member 21 from that upon which the top holder 22 is mounted is a friction device 23 embodying therein a sleeve 24 which is secured to the pivot member 21 by a cotter pin 25 and said sleeve 24 therefore rotates in unison with said pivot member. The sleeve 24 is recessed at 26 to provide a space for receiving a coil spring 27 surrounding the pivot member 21 and one extremity of said spring is connected to the arm 19 and the other extremity to the sleeve 24 in a manner to cause the top holder 22 to engage a stop provided upon the arm 19 at which time the top holder will be located in a position to support the small end portion of the filling car-

rier 12 when said carrier is located in transferring position.

Mounted upon and extending around the periphery of the sleeve 24 of the friction device 5 23 is a holder 28 for a friction member 29. The holder 28 is constructed as a band of sheet material and has a circular clamping portion 30 embodied therein which is adapted to encircle and grip the sleeve 24. Relatively parallel extensions 10 31 and 32 of the circular portion 30 are adapted to be sprung toward each other by means of a bolt 33 and thumb nut 34 in causing the circular portion 30 to grip the sleeve 24, and a resilient supporting arm 35 for the friction member 29 is formed integral with the extension 32. The extension 31 terminates in an angular portion 36 which is adapted to engage the extension 32 and which constitutes a stop to limit the movement of the outer extremity of the extension 31 15 toward the extension 32, thereby making the gripping action of the circular portion 30 more effective.

The friction member 29 is constructed of flexible material as, for example, rubber, or a material having the characteristics of rubber and is provided with a bevelled surface 37 which is adapted to underlie the filling carrier 12 which is located in transferring position and yieldingly engages the filling thereon in a manner 20 to prevent said carrier from rotating in the hopper 11. The friction member 29 will furthermore act as an aid in supporting the carrier 12 with which it contacts. It is desirable that the material of which the friction member 29 25 is constructed shall be sufficiently flexible so that it will engage the filling upon the filling carrier with a gentle yielding action to the end that said member will effectively grip the filling material and thereby prevent the carrier from rotating without injuring the filling.

The friction member 29 is adjustably mounted upon the resilient arm 25 to move toward and away from the filling carrier 12 with which it is adapted to contact in order that it may be 30 correctly positioned with respect to said filling carrier. The friction member 29 is positioned upon the arm 35 by means of a guide 38 which is constructed as an inverted U-shaped member, the parallel arms 39 of which engage the opposite edges of the arm 35, see Fig. 4, and the friction member 29 is clamped between the guide member 38 and the arm 35 by means of a bolt 40 and its nut 41, said bolt passing through a slot 42 provided therefor in the friction member 29, 35 see Fig. 5.

It will be understood that the arm 19, pivot member 21, top holder 22, sleeve 24 and spring 27 are all old and well known in the art and that the top holder 22 tips downwardly to release the carrier 12 every time a transfer is made. Applicant has utilized the pivot member 21 and sleeve 24 as a support for his improved friction device 23.

In the operation of the loom as the hopper 11 is rotated to successively position the filling carriers 12 into transferring position, the surface of the filling of the carrier next to be transferred will engage the bevelled surface 37 of the friction member 29 causing the lower portion 45 of the resilient arm 35 upon which the friction member 29 is mounted to yield slightly toward the support 24. In addition, the bevelled surface 37 of the friction member 29 will engage the filling with a gentle flexing contact which 50 will prevent the carrier from the rotating and

at the same time not injure the filling during the interval that the carrier is located in transferring position, and at the time that the carrier is transferred to the shuttle. When the transfer is made the friction device 23 will rock 5 in unison with the top holder 22 as the latter releases the carrier, and said friction device will act to support and guide the carrier during its transfer from the hopper to the shuttle.

In Fig. 6 I have illustrated a modified embodiment of my invention in which 43 comprises a holder constructed as a band of sheet material having a circular clamping portion 44 embodied therein which is adapted to encircle and grip a sleeve 24. Relatively parallel extensions 10 45 and 46 of the circular portion 44 are adapted to be sprung toward each other by means of a bolt 33 and thumb nut 34 in causing the circular portion 44 to grip the sleeve 24, and a resilient supporting arm 48 for a friction member 29 is formed integral with the extension 46. The resilient arm 48 is bent outwardly from the extension 46 and then extends downwardly and beneath the circular clamping portion 44 and terminates in an end portion 49 to which the friction member 29 is secured. The extension 45 terminates in an angular portion 47 which is adapted to engage the extension 46 and constitutes a stop to limit the movement of the outer extremity of the extension 45 toward the extension 46, thereby making the gripping action of the circular portion 44 more effective.

The friction member 29 is adjustably mounted upon the portion 49 of the resilient arm 48 by means of an inverted U-shaped guide member 38, bolt 40 and nut 41 in exactly the same manner as is the friction device previously described in connection with the disclosure illustrated in Figs. 1 to 5 inclusive. The action of the device illustrated in Fig. 6 is exactly the same as that of the device illustrated in Figs. 1 to 5 inclusive, except that there may be slightly more flexibility to the resilient arm 48 than there is to the resilient arm 35.

I claim:

1. A friction device for the filling carriers of a filling replenishing loom comprising, in combination, a support, a holder adjustably clamped thereto, and having a resilient arm embodied therein and a friction member adjustably mounted upon said arm and adapted to yieldingly engage the filling on a filling carrier next to be transferred from a hopper for a reserve supply of filling carriers to a shuttle located therebeneath and prevent said carrier from rotating in said hopper, said friction member also constituting a guide for the carrier during its transfer from the hopper to the shuttle.

2. A friction device for the filling carriers of a filling replenishing loom comprising, in combination, a support, a holder comprising a band surrounding said support and having a resilient arm embodied therein, means to clamp said holder to the support, and a friction member mounted upon said arm and adapted to yieldingly engage the filling on a filling carrier next to be transferred from a hopper for a reserve supply of filling carriers to a shuttle located therebeneath and prevent said carrier from rotating in said hopper, and also support and guide the carrier during the transferring operation.

3. A friction device for the filling carriers of a filling replenishing loom comprising, in combination, a support, a holder comprising a band surrounding said support and having a resilient arm 75

embodied therein, means to clamp said holder to the support, a flexible friction member mounted upon said arm and adapted to yieldingly engage the filling on a filling carrier next to be transferred from a hopper for a reserve supply of filling carriers to a shuttle located therebeneath and prevent said carrier from rotating in said hopper, means to guide said friction member upon said arm, and means to clamp the guide and friction member to the arm.

4. A friction device for the filling carriers of a filling replenishing loom comprising, in combination, a support, a holder comprising a band surrounding said support and having a circular 15 clamping portion provided with relatively parallel extensions and a resilient arm embodied therein, means to clamp said circular portion to the support, a flexible friction member mounted upon said arm and adapted to yieldingly engage the filling on a filling carrier next to be transferred from a hopper for a reserve supply of filling carriers to a shuttle located therebeneath and prevent said carrier from rotating in said hopper, and means to clamp said friction member to the 20 arm.

5. In a filling replenishing loom the combination of a rotary hopper for filling carriers, a transerrer stud, an arm fast to said stud, a sleeve pivotally mounted upon said arm, a holder fast to said sleeve and having a resilient arm embodied therein, and a friction member mounted upon said resilient arm and adapted to engage the filling on a filling carrier next to be transferred from said hopper to a shuttle located therebeneath and prevent said carrier from rotating in 10 the hopper.

6. In a filling replenishing loom the combination of a rotary hopper for filling carriers, a transerrer stud, an arm fast to said stud, a sleeve pivotally mounted upon said arm, a holder comprising a band adjustably clamped to said sleeve and having a resilient arm embodied therein, and a flexible friction member adjustably mounted upon said resilient arm and adapted to engage the filling on a filling carrier next to be transferred from said hopper to a shuttle located therebeneath and prevent said carrier from rotating in the hopper.
